(57) **CLAIM**

The ornamental design for a brassiere with crossing back straps and front closure, as shown and described.

DESCRIPTION

FIG. 1 is front view of a brassiere with crossing back straps and front closure;

FIG. 2 is a right side elevational view thereof, the left side elevational view being a mirror image; and,

FIG. 3 is a back view thereof.

The broken lines shown in the drawings are for illustrative purposes only and form no part of the invention.
